CLAIM

The ornamental design for bar stool, as shown and described.

DESCRIPTION

FIG. 1 is a perspective view of a bar stool, showing my new design;
FIG. 2 is a front view thereof;
FIG. 3 is a rear view thereof;
FIG. 4 is a side elevational view, the opposite side being a mirror image thereof;
FIG. 5 is a bottom view thereof;
FIG. 6 is a top view thereof;
FIG. 7 is a perspective view of a modified form of the design shown in FIGS. 1 through 6;
FIG. 8 is a front view thereof;
FIG. 9 is a rear view thereof;
FIG. 10 is a side elevational view, the opposite side being a mirror image thereof;
FIG. 11 is a bottom view thereof; and
FIG. 12 is a top view thereof.
